PORTABLE SWIMMING POOL DIGGER

Vernon L. Bartley, 801 Charlston St., Mobile, Ala.

Filed Dec. 6, 1957, Ser. No. 701,240

6 Claims. (Cl. 37—192)

This invention relates to a machine for making excavations and more particularly to a machine for excavating an area within which to subsequently construct a swimming pool.

An object of the invention is to provide a machine that is comparatively easily handled and operated with a minimum of help. My machine is easily portable and set-up on the site at which an excavation for a swimming pool is to be made.

My entire assembly can be set up in a short while and be made ready for digging. After the hole is dug, the digging assembly can be removed from the bottom of the center member of my machine, two of the legs or frames removed and replaced 120° apart and the top of the three sections disassembled and three lever lifting parts bolted to the three sections with a long threaded screws. This adjusts my machine so that it is a tripod that can be used as a crane for lifting and lowering pre-fabricated swimming pool parts or a monolithic part to install the same in place.

Accordingly, it is an object of this invention to provide a machine which is capable of being easily transported from one job to another, the machine having three sections and a center member that are adjustably connected together so that they can be moved parallel to each other in the form of a trailer, or they can be arranged as a truss with the span extending over the area that is to be dug and provided with a digger to remove the soil from the excavation area or can be arranged as a hoist frame for lifting and lowering parts in the excavation.

Other objects and features of importance such as the practicability of the construction and the rapidity with which the swimming pool excavations or other types of excavations may be made, will become apparent in following the description of the illustrated forms of the invention.

Figure 1 is an elevational side view of a machine constructed in accordance with the invention, the machine illustrated being in the process of excavating a cavity which will subsequently receive a pool liner and a frame section at the center of the machine being omitted for clarity.

Figure 2 is a fragmentary top view of the invention.

Figure 3 is an elevational view of the machine showing it used for grading the soil around the excavation, this view having the digger removed and replaced by a soil levelling attachment and a frame section at the center of the machine also being omitted for clarity.

Figure 4 is an elevational view of my machine showing it used as a hoist to lower the parts of the swimming pool in the excavation.

Figure 5 is a top view of the machine in the position in which it may be transported.

Figure 6 is an elevational view of the machine in Figure 5 showing the same attached to the back of a small truck by a conventional trailer hitch.

Figure 7 is an enlarged sectional view of the center

2

member of my machine and showing a part of the mechanism for operating the machine.

Figure 8 is an enlarged sectional view taken on the line 8—8 of Figure 7.

Figure 9 is a fragmentary sectional view taken on the line 9—9 of Figure 7.

Figure 10 is a fragmentary elevational view showing a chain sprocket, arms and brace assembly.

Figure 11 is a fragmentary sectional detail of a portion of Figure 10.

Figure 12 is a modification showing the motor on a hinged stand.

In the accompanying drawings there is shown a machine 10 which is constructed to fulfill the aims of the invention. This machine is designed to excavate cavities in the ground within which to install swimming pool parts. The machine is made of a number of sections connected to a center member that is capable of operating a number of tools. There are four sections 12, 14, 16 and 18 and each is made of an open frame truss. The center member 20 of the machine is shown in detail in Figures 7—9 and includes an upper plate 22 and a lower plate 24 that are spaced apart by a center hollow column 26. The inner ends of the four sections are attached to the upper and lower plates 22 and 24 by clamps 30. Each clamp consists of a hinge plate 31 attached to a removable pin 32 at the end of bracket 33 on a section (Figure 7). With clamps such as clamp 30 at the top and bottom of center section 20, the sections form a rigid frame as shown in Figure 2. Four anchors 36 are spaced 90° from each other with the lines of intersection extending between the anchors being directly above the center of the excavation that is to be made. Means hereinafter described are provided for securing the outer ends of the sections to the anchors. These means are shown as dovetail keys 38 in the anchors 36 and slots 40 at the ends of the sections 12, 14, 16 and 18. The dovetail slots terminate above the ground level whereby the anchors serve as structural supports for the machine.

A source of power, for example, gasoline motor 42, or an electric motor (not shown) is mounted on section 14. This motor can be directly attached by motor mounts onto section 14 as shown in Figure 1 or can be mounted on a frame 46 as shown at 42a in the modification of Figure 12. The latter construction is preferred so that the motor does not have to be elevated as shown in Figure 4, when the equipment is used as a crane. So that the motor remains horizontal, it may be hinged as at 47 to the motor frame 46 and an adjustable leg frame 48 attached to the motor and adapted to engage the ground to retain the motor horizontal even though section 14a is at an angle. A universal joint 49 drivingly connects driveshaft 50a to the motor. Driveshaft 50 of Figure 1 can also have a universal joint to take care of minor misalignment with the motor. A sufficient number of bearings 52 for shaft 50 are carried by section 14 and the inner end of the shaft 50 has a wobble slip clutch 54 connecting it to shaft 55 (Figure 7).

After setting up the machine as shown in Figure 2, digging may commence. The digging is achieved by an endless conveyor type digger 57 which empties onto a conveyor 58. The conveyor 58 disposes the dug soil in a circle around the excavation so that this soil can later be graded by my machine (Figure 3).

The digger 57 is formed of an endless chain 60 entrained around sprocket 61 on transverse shaft 62. The shaft is carried by a depending carrier 63 located below plate 24. The carrier carries a pair of digger frame sides 65 and 66, (Figures 1 and 10) whose outer ends accommodate a transverse shaft 68 on which sprocket 69 is mounted. Endless chain 60 extends around sprocket 69.

and around the previously mentioned sprocket 6 (Figure 7). There are bearings 70 and 71 at the ends of shaft 62 mounting it for rotation. A worm wheel 73 is secured to shaft 62 (Figure 9) and a worm gear 74 is enmeshed with it. A plurality of spaced digger buckets 75 are suitably pivoted to the links of chain 60 and these do the actual excavation. Each bucket has a lateral pin 76 (Figure 7) which is adapted to contact stop 77 on a part of carrier 63 and tilt the bucket as it reaches the top of its travel.

The conveyor 58 comprises a conveyor belt 79 extending around pulley 80 on shaft 62. A number of intermediate pulleys 81 (Figure 8) are on spindles 82 and constrain the travel of the conveyor belt. Conveyor frame 83 extends from the carrier and has elongated sides 84 (Figure 1) on which the outer end conveyor roller 85 is carried.

As seen in Figure 7 when the dug soil is dumped from buckets 75 it spills onto the endless conveyor 79 for discharge in mound 88 (Figure 1) considerably removed from the edge of the excavation. A concavo-convex baffle 89 is on shaft 62 between roller 80 and the sprocket 61. This assures that the soil which is emptied from buckets 75 will be deposited on the endless conveyor and discharged.

The means for rotating shaft 62 have partially been described. They include worm wheel 73 and worm gear 74 which is secured to a polygonal shaft 90. This shaft has a plurality of spaced bearings 91 thereon which are guided in the hollow drive shaft 92. This drive shaft is concentric with hollow column 26 and has upper and lower bearings 93 and 94 therebetween. Shaft 55 and polygonal shaft 90 have a pair of miter gears 94' drivingly connecting them so that power from the motor 42 or 42a is delivered to shaft 90. The shaft 90 is polygonal since it must be capable of axially sliding and yet drive worm 74 and be driven by one of the miter gears 94. Hand crank 95 which is optionally usable upon disengagement of clutch 54, is attached to the upper end of shaft 90 and located above gear case 96 that is attached to the upper plate 22. This manually powers shaft 62 for the digger and conveyor. However, the digger, conveyor and their carrier 63 rotate as a unit about the longitudinal axis of shaft 90. This is achieved by rotating the hollow driveshaft 92 that has a flange 99 at its lower end bolted or otherwise attached to carrier 63. The upper end of the hollow driveshaft has a gear 100 fixed to it. An optionally usable hand wheel 101 has a pinion 102 on it and is mounted in bearings 103 in upper plate 22. The hand wheel shaft passes through an opening in the gear case 96 and the pinion 102 is meshed with gear 100. Rotation of the hand wheel 101 will cause the hollow driveshaft 92 to be driven thereby rotating the entire carrier with the tools thereon in a circular travel. Clutch 104 is slidably mounted on shaft 55. Gear 105 idles on shaft 55 until engaged by clutch 104. Then the drive connection between shaft 55 and gear 105 is established. This gear is meshed with the gear 106 that it is either made on gear 100 or is separably made and fastened in place thereon. Hand control 107 is attached to clutch 104 so that the operator has the option of using the hand wheel 101 or power from shaft 55 to actuate the hollow driveshaft 92. Cable 109 is movably attached to the depending circular track 110 on the truss sections and is under the control of the operator. This cable steadies and guides the digger as it moves in a circular path of travel. The end of the cable can be connected to a carriage movable along the track 110 and the length of cable 109 can be made longer or shorter depending on the depth of cut that is to be taken. After the first cut is taken by having the digger approximately horizontal (resting directly on the ground) the second cut is made a little deeper while the third cut is deeper than that. Finally, the cutter will be practically vertical

thereby forming a semi-spherical excavation 115 into which a pool liner 116 can be lowered. First, though, it is suggested that the circular accumulation of soil 88 be graded. For this purpose a grading tool 120 is attached to the center section 20 of my machine. The grading tool is made of an endless conveyor 121 which may have cleats on it. The endless conveyor has a conveyor frame 122 and rollers carried by transverse shafts on the frame. The shaft of the innermost roller is drivingly connected to a gear box 123 which has shaft 124 extending from it and on which pulley 125 is fixed. A drive belt 126 is engaged with pulley 125 and with the pulley 127. The pulley 127 is secured to shaft 90 after the carrier 63, digger and conveyor 79 are removed from the flange 99 of hollow driveshaft 92. In their place plate 128 is bolted. The gear box 123 is secured to this plate and the plate 128 is provided with suitable wheels travelling along the circular track 110 so that the entire levelling assembly 120 can be rotated about the longitudinal axis of shaft 90 with hollow driveshaft 92. The same structure from flange 99 upward, that is in Figure 7, is used with the soil levelling attachment. It is preferred that the endless conveyor have its inner roller shaft mounted so that the conveyor will pivot about that shaft so that its own weight keeps the conveyor pressed downward at all times while it is operating. The slope shown in Figure 3 which is desired for a swimming pool, is automatically achieved in this way.

After the soil has been levelled the precast concrete liner 116 can be lowered. It is very apparent that this is a sequence which can be deviated from in that the liner parts or part may be lowered before final grading. Should this be the case, machine 10 is adjusted as shown in Figure 4 after removing the track 110 therefrom. A long screw 140 has a flange at its upper end by which the screw is bolted to flange 99 in place of carrier 63 or spider or plate 128. Nut 142 is on screw 140 and has lateral ears to which a plurality of links 144 are pivoted. The opposite ends of the links are pivoted to brackets on three of the sections 12, 16 and 18 of the machine. Section 14 has the motor on it in the embodiment of Figure 4. The preferred arrangement will be to have section 14a connected to one of the links 144 and another of the sections remain horizontal instead of section 14 (Figure 12). In any case, the three sections which are to be made into a tripod have their upper clamps 30 removed and rebolted to the center member 20 at a 120° spacing, in which the upper clamps 30 are replaced with links 146 after the three sections have been pivotally actuated about the pins of their lower clamps 30 to assume the position shown in Figure 4. Screw 140 is actuated prior to installation of the links 146 to achieve the tripod position through the action of the nut 142 thereon and links 144.

Overhead rail 150 is secured to the lower chord of the horizontal section 14 and a block and tackle 152 is mounted on the overhead track 150. Legs 154 are placed under the outer end of the horizontal section 14 so that the machine in essence becomes a crane with the ability to support the block and tackle in a position to raise, lower and place heavy swimming pool parts, as the precast concrete liner 116.

In order to dig smaller or larger holes the length of the cutter 57 can be varied by removing it and replacing it with another of a different length. Accordingly, the sides 65, 66 of the cutter 57 are mounted so that they can be separated from carrier 63 quickly. Split bearings 159 and 160 have their sections formed with semi-circular rims that fit in the circular grooves 161 and 162 of bearings 163 and 164 mounted on the walls 165 and 166 of carrier 63. They are concentric with shaft 62 enabling the digger to oscillate about the longitudinal axis of the shaft.

As seen from Figure 7, the directions of rotation may be varied. There is no structural obstacle to rotating the

driveshaft 92 or the shaft 90 in a clockwise or counter-clockwise direction. This is especially important when the grader attachment (Figure 3) is used so that the grading can be done in either direction. The hand controls are optional and are capable of being engaged and disengaged by merely pulling or pushing the shafts that have hand wheel 101 and handle 95 thereon.

It is an important feature of the invention to have it capable of easy maneuverability and transportation. I have shown a part of a small pick-up truck 170 with a trailer hitch 171 thereon. The part 172 of the hitch is bolted to the bottom plate 24 of center member 20 of my machine. The open frame truss sections can be unbolted from the member 20 and suitably rebolted thereto in parallel relation as shown in Figure 5 with the use of links 174 of correct length. Separably mounted wheel trucks 175 are attached to the rear ends of the sections 12, 14, 16 and 18 after they are bound together by ties 176 or otherwise rigidly connected.

It is understood that various changes may be made in my invention without departing from the following claims.

What is claimed as new is as follows:

1. In an excavating machine, the combination of a supporting frame including a center member and a plurality of elongated frame sections connected to and extending radially outwardly from said center member, means at the outer ends of said frame sections for anchoring the same to the ground, a carrier rotatable in a horizontal plane at the underside of said center member, means for rotating said carrier, an endless conveyor type digger pivoted at one end thereof to said carrier for raising and lowering movement, means for driving said digger whereby the same may excavate a substantially semi-spherical cavity in the ground under said frame when said carrier is rotated, an annular track provided at the underside of said frame sections concentrically with said center member, means movable along said track and connected to the outer end of said digger for suspending the same therefrom, and conveyor means connected to said carrier for rotation therewith and communicating with the pivoted end of said digger, said conveyor means extending radially outwardly from said carrier beyond the outer end of the digger whereby to transfer earth from the digger to the ground exteriorly of the stated cavity.

2. The device as defined in claim 1 together with a horizontal shaft rotatably journaled in said carrier and having the respective inner ends of said digger and of said conveyor means mounted thereon.

3. The device as defined in claim 1 together with a horizontal shaft rotatably journaled in said carrier and having the respective inner ends of said digger and of said conveyor means operatively connected thereto, said means for rotating said carrier including a vertical tubular shaft rotatably journaled in said center member and having said carrier secured to its lower end, said means for driving said digger including a vertical inner shaft rotatably journaled in said tubular shaft and operatively

connected at its lower end to said horizontal shaft, and a source of motive power provided on said frame and operatively connected to said tubular shaft and to said inner shaft.

5. In a machine of the character described, the combination of a supporting frame, a carrier rotatable in a horizontal plane at the underside of said frame, means for rotating said carrier, an endless conveyor type digger removably and pivotally connected at one end thereof to said carrier for raising and lowering movement, driving means provided on said frame and operatively connected to said digger whereby the same may excavate a substantially semi-spherical cavity in the ground under the frame when said carrier is rotated, conveyor means 10 removably connected to said carrier for rotation therewith, said conveyor means communicating with the pivoted end of said digger and extending outwardly beyond the outer end of the digger whereby to transfer earth from the digger to the ground under the frame exteriorly of the stated cavity, and earth grading means removably attachable to said carrier in substitution for said digger and for said conveyor means, said grading means being operably connectable to said driving means for grading the transferred earth at the exterior of the stated cavity during rotation of said carrier.

15. In a machine of the character described, the combination of a supporting frame including a center member and a plurality of elongated frame sections adjustably attached at one end thereof to said center member and 20 radiating therefrom, said frame sections being movable from a substantially horizontal position wherein said center member is substantially coplanar therewith to a downwardly and outwardly extended position wherein said center member is supported at an elevation above 25 their outer ends, means removably mounted at the underside of said center member for excavating a cavity in the ground under said frame when said frame sections are in their horizontal position, and block and tackle means 30 radiating therefrom, said frame sections being movable from a substantially horizontal position wherein said center member is substantially coplanar therewith to a downwardly and outwardly extended position wherein said center member is supported at an elevation above 35 their outer ends, means removably mounted at the underside of said center member for excavating a cavity in the ground under said frame when said frame sections are in their horizontal position, and block and tackle means 40 removably attachable to said frame in substitution for said last mentioned means when the frame sections are downwardly and outwardly extended.

45. The device as defined in claim 5 wherein said frame sections are attachable in a substantially mutually parallel relation to said center member to facilitate transportation of said frame.
